UNITED STATES PATENT OFFICE.

FRANK D. BULLARD, OF LOS ANGELES, CALIFORNIA.

PIPE-WRENCH.

SPECIFICATION forming part of Letters Patent No. 742,389, dated October 27, 1903.

Application filed March 26, 1903. Serial No. 149,689. (No model.)

To all whom it may concern:

Be it known that I, FRANK D. BULLARD, a citizen of the United States, residing at Los Angeles, in the county of Los Angeles and State of California, have invented new and useful Improvements in Pipe-Wrenches, of which the following is a specification.

The object of my invention is to provide a pipe-wrench which will operate effectively upon pipes of several different sizes and which will automatically adjust itself to the different sizes. I accomplish this object by the wrench described herein and illustrated in the accompanying drawings, in which—

15 Figure 1 is a side elevation of my wrench in its normal position. Fig. 2 is an end elevation of my wrench looking at it from the rear or handle end. Fig. 3 is a side elevation of the wrench in its open position gripped by 20 the hand ready to be placed on a pipe.

In the drawings, A is the outer jaw of my wrench, the upper or inner face of which is preferably in the form of a slightly-obtuse angle with teeth A' therein, as shown. This 25 jaw could be circular in the toothed section, if desired. To this jaw is pivoted the handle B. To the outer jaw intermediate its connection with the handle is pivoted the inner jaw C, which has a circular face provided with 30 teeth C' presented toward the teeth of the outer jaw. The inner jaw is provided with a rearwardly-projecting shank, which bears upon a boss B', formed on the edge of the handle at the forward end thereof just back 35 of its junction with the outer jaw, the back of which shank is roughened, so that in use the thumb may not slip thereon. A small portion C'' of the shank projects down the side of the boss and turns into a groove B'' in 40 the boss. This groove is near the front face of the boss and follows the contour-line thereof and guides the shank of the inner jaw to always keep it in engagement with the boss of the handle, and thereby prevents the handle 45 from accidentally turning on the pivot which joins it to the outer jaw. A socket D (shown in Fig. 1) houses one end of spring E, the other end of which surrounds stud F, mounted in the outer jaw. This spring keeps 50 the jaws normally closed, as shown in Fig. 1.

In operating the wrench the handle is gripped with the fingers of the hand, and the

thumb is placed on the shank of the inner jaw, and it is pushed forward, passing down in front of the boss which carries the free 55 end of the outer jaw backward toward the handle, thereby causing the jaws to separate when they are placed on pipe G, as shown in Fig. 3. As soon as the wrench is on the pipe the thumb is removed, and the spring causes 60 the jaws to grip the pipe, when by turning the handle in the proper direction the pipe may be screwed into or out of engagement with another section, as desired.

By having a boss on the handle to engage 65 the shank of the inner jaw the jaws may be opened wider and a greater range of use is obtained in a wrench than if such boss were not used. By having the inner face of the outer jaw the form of an obtuse angle and 70 the outer face of the inner jaw circular in form the jaws bear upon the pipe, no matter what its size may be, at three points, and the crushing strain upon the pipe comes on a line at an angle to the diameter of the pipe, and 75 thereby avoids all danger of crushing the pipe. When used for nuts, the teeth on the jaws may be omitted, if desired. The tooth-section of the jaws may be removable sectors, if desired. 80

Having described my invention, what I claim as new, and desire to secure by Letters Patent, is—

1. A pipe-wrench composed of a handle having a boss on the edge near the inner end 85 thereof; an outer jaw pivoted to the inner end of said handle in front of the boss; an inner jaw having a shank pivoted to said outer jaw a little in front of the connection between said outer jaw and handle, said 90 shank being adapted to pass down in front of said boss when the jaws are opened for placement on a pipe and to be raised by said boss to close the jaws when the wrench is being operated. 95

2. A pipe-wrench composed of a handle having a boss on the inner end thereof; a groove in said boss; an outer jaw pivoted to the inner end of said handle, an inner jaw, having a shank, pivoted to said outer jaw near its junction with the handle, said shank being adapted to pass down in front of said boss and having a portion extending into said groove in said boss; a socket in the shank of 100

said inner jaw; a spring in said socket adapted to bear against said outer jaw.

3. A pipe-wrench composed of a handle having a boss on the edge near the inner end 5 thereof; an outer jaw pivoted to the inner end of said handle in front of the boss having its upper face in the form of an obtuse angle with teeth therein; an inner jaw having a circular face with teeth therein projecting 10 toward the teeth of the outer jaw and a rearwardly-projecting shank pivoted to said outer

jaw a little in front of the pivotal connection between said outer jaw and handle, said shank of said jaw being adapted to bear against the boss of said handle.

In witness that I claim the foregoing I have hereunto subscribed my name this 20th day of March, 1903.

FRANK D. BULLARD.
